UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

HARNESS MOTION FOR LOOMS.

Application filed June 3, 1924. Serial No. 717,539.

To all whom it may concern:

Be it known that I, JONAS NORTHRUP, a citizen of the United States, residing at Hopedale, in the county of Worcester and State of Massachusetts, have invented certain new and useful Improvements in Harness Motions for Looms; and I do hereby declare the following to be a full, clear, and exact description of the invention, such as will enable others skilled in the art to which it appertains to make and use the same.

The present invention relates to an improvement in harness motions for looms.

The object of the invention is to re-organize and improve harness motions, and the invention consists in the harness motion hereinafter described and particularly defined in the claims.

In the accompanying drawings illustrating the preferred form of the invention, Fig. 1 is a front view of the motion; Fig. 2 is a sectional elevation; Fig. 3 is a plan of one end of the arch showing the supporting brackets for the motion; Fig. 4 is an end elevation of a harness strap pulley or sheave; Fig. 5 is a section of the arch showing the mode of supporting the harness operating shaft; Fig. 6 is an end elevation of a portion of the loom showing the actuating mechanism for the motion; Fig. 7 is a front elevation of the same; and Fig. 8 is a sectional elevation on the line 8—8 Fig. 6.

The illustrated embodiment of the invention is described as follows: The end frames 1 of the loom support the arch, of which the end posts 2 rise from the frames to the cross-channel 3 of the arch and extend from end post to end post. The harnesses are two in number, the front harness 4 and the rear harness 5. The harness 4 is supported by four straps 6 provided with hooks at their lower ends to engage eyes in the harness frame. These straps 6 extend upward to the sheaves 7 mounted on the harness shaft 8. The straps 6 are received on a smaller portion 9 of the sheaves 7, being secured thereto by means of the screw 10. When the shaft 8 turns to the left, as viewed in Fig. 4, the straps 6 unwind from the sheave and permit the front harness 4 to descend. The rear harness is

similarly supported on the straps 11 which are provided on their lower ends with hooks which engage eyes on the harness 5 and extend upward to and are received on a larger portion 12 of the sheave 7, being secured thereto by means of the screws 13. When the harness shaft 8 turns to the left, as viewed in Fig. 4, the harness straps 11 are wound up on the larger portions 12 of the sheaves, and the rear harness 5 is thereby raised. The stroke of the rear harness is somewhat longer than the stroke of the front harness in order to bring the threads carried by the rear harness into the same shed plane as formed by the front harness. The harness shaft 8 is mounted at one end in the bearing 14 in the bracket 15 secured to the cross-member 3 of the arch. Collars 16 and 17 hold the shaft 8 from endwise movement. Additional supports 18 for the harness shaft 8 are provided. These supports 18 have shanks which are received in holes in the cross-member 3 of the arch, being secured in place therein by the set screws 19. Each support 18 is provided with a bearing 20, which is open at the top and supports in the opening the harness shaft. The harness shaft 8 extends across the loom only far enough to carry the sheaves for supporting the harnesses and terminates, in the illustrated embodiment, before it reaches the end of the cross-member 3 of the arch, as shown at the left hand end of Fig. 1. A bottom harness shaft 21 is employed which is mounted in bearings 22 which form parts of the brackets 23 which are bolted at 24 to portions 25 of the frame of the loom. On the bottom harness shaft 21 are secured two sheaves 26 similar to the sheave 7 on the top harness shaft 8. These sheaves are connected by straps 27 and 28 to the jack sticks 29 and 30, respectively, the jack sticks 30 being hooked on the lower member of the harness frame 4, and the jack sticks 29 being hooked to the lower member of the harness 5 in the usual manner. The harnesses are raised and lowered by oscillations of the upper harness shaft 8. When the harness 4 is lowered, the harness 5 is raised, and the harnesses are kept under control by the bottom harness shaft and the bottom straps.

The upper harness shaft 8 is provided on its right hand end, as viewed in Fig. 1, with a pinion 31. This pinion is actuated by a segment gear 32 pivoted at 33 on the bracket 15. Oscillations of the segment gear 32 impart oscillating movements to the upper harness shaft 8. The segment gear is actuated by the link 34 which is provided with a boss 35 at its upper end in 10 which is pivotally received the crank pin 36. This crank pin is received in a radial slot 37 in the segment gear 32, and is adapted to be secured in any position in the slot. With a given stroke of the actuating link 15 34 the stroke of the segment gear may be varied. This provides for increasing and decreasing the harness movement. The lower end of the actuating link 34 is provided with a yoke plate 38. This plate has 20 rearwardly extended flanges 39 which engage the edges of the crank disk 40 mounted on the shaft 41. Inturned lips 42 extend toward the shaft from the flanges 39 and embrace the disk 40 and permit the plate 25 38 to rise and fall on the disk wheel, holding it from detachment therefrom by lateral movement. The yoke plate 38 is provided with an opening 43 through which the crank pin 44 projects. On the front 30 side of the plate there is attached a cam plate 45 provided at its ends with ears 46. This cam plate 45 is provided with an opening 47, the outline of which is shown in Fig. 6, the outline being indicated by the 35 reference character 48. The cam roll of the crank pin 44 projects into this opening 47 in the plate 45. The cam plate is secured to the yoke plate by means of the bolts 49, the yoke plate being provided with ears 50 slotted at 51 for the reception of the bolts 49. These slots 51 are curved to permit 40 turning of the cam plate with respect to the yoke plate, so as to vary the timing of the actuation of the link 34 and therefore 45 of the harnesses. The front side of the yoke plate is provided with two ears 52 which receive adjusting bolts 53 by which the position of the cam plate may be adjusted on the yoke plate, after which the cam plate 50 will be secured in adjusted position by means of the bolts 49.

The opening 47 in the cam plate is provided with a cover 54 normally held closed by a spring clip 55. The cover will be 55 opened to introduce oil for lubricating the crank pin and cam, and then closed to prevent the access of lint and dust to the cam. The cam plate is curved as shown in the 60 outline indicated by the reference character 48, that is to say, so that the motion imparted to the yoke by the crank pin has two dwells in it, namely at the top and at the bottom, so that during a rotation of the crank disk the cam plate is lifted during 65 the time the crank disk occupies one

of the notches in the ends of the cam plate. Then having raised it up to its top position, the cam passes over the arcuate surface of the upper part of the cam, and the cam stands fast during such movement. 70 Thereafter the crank pin enters the other recess and the plate is depressed. At the end of the depression another dwell occurs. This produces the dwells in the motions of the harnesses to allow time for the shuttle 75 to pass through the sheds.

By varying the position of the cam plate on the yoke plate, and by changing its angle with respect thereto, the timing of the dwells and movements of the yoke plate 80 and therefore of the harnesses may be varied. Thus, viewing the structure as illustrated in Fig. 6, by turning the cam plate to the right or to the left on the yoke plate 38, the time of actuation of the actuating link 34, and therefore the time of actuation of the harnesses, may be made earlier or later. The actuating link is provided with a bolt or slot connection 56 by means of which the length of the link may be varied. 85 With variations in the position of adjustment of the connections 36 to the segment gear, the length of the link may be varied by this bolt and slot connection 56 to adapt it to the position of adjustment preferred. 90 The shaft 41 is supported near its end in the bearing 57 mounted on the portion 58 of the frame of the loom. 95

It is to be noted that the sheaves or pulleys on the harness shafts may be described as differential harness connections, inasmuch as they move the different sheaves different distances so as to secure register of sheds made by the different harnesses. 100

Having thus described the invention, 105 what is claimed is:

1. A harness motion for looms having, in combination, harnesses, an upper harness shaft, a lower harness shaft, connections between the harnesses and harness shafts, a pinion on the upper harness shaft, a segment gear engaging the pinion, a link for actuating the segment gear, a yoke on the lower end of the link provided with a slot having two arcuate dwell surfaces, a crank pin engaging the slot for actuating the link and thereby actuating the harnesses with dwells in their movements. 110

2. A harness motion for looms having, in combination, two harnesses, top and bottom harness shafts, connections between the harness shafts and the harnesses, one of said harness shafts being provided with a pinion, a segment gear engaging the pinion, slotted yoke and crank means, and connections between said slotted yoke and crank means and the segment gear for actuating the latter, having provision for turning the yoke for varying the timing of the actuation of the harnesses. 120 125 130

3. A harness motion for looms having, in combination, harnesses, top and bottom harness shafts, connecting mechanism for actuating the harness shafts, a link operatively connected with the connecting mechanism provided with a slotted yoke, a crank adapted to engage the slot of the yoke, means for adjusting the position of the yoke with respect to the crank for varying the time of the harness actuation. 10
